UNITED STATES PATENT OFFICE.

BERTHA M. GEEN, OF KELOWNA, BRITISH COLUMBIA, CANADA.

BUTTON-FORM.

1,305,275.

Specification of Letters Patent. Patented June 3, 1919.

Application filed November 1, 1918. Serial No. 260,683.

To all whom it may concern:

Be it known that I, BERTHA M. GEEN, a subject of the King of Great Britain, residing at Kelowna, in the Province of 5 British Columbia and Dominion of Canada, have invented certain new and useful Improvements in Button-Forms, of which the following is a specification.

This invention relates to buttons and particularly to that class of buttons which are covered with textile material such as cloth, the invention having for its object to provide a separable button form, the parts of which can be quickly assembled and covered 10 by an unskilled person without trouble and which may be used over and over by disengaging the parts and substituting a new piece of cloth for that previously covering the button.

With these objects in view, together with others which will appear as the description proceeds, the invention resides in the novel formation, combination and arrangement of parts, all as will be described more fully 20 hereinafter, particularly pointed out in the claims, and illustrated in the accompanying drawings, in which:

Figure 1 is an enlarged central, transverse sectional view of the improved button.

Fig. 2 is a horizontal sectional view on the line 2—2 of Fig. 1.

Fig. 3 is a transverse sectional view of a portion of the button showing a modification, and

Fig. 4 is a similar view showing a further modification.

In the drawings, 10 indicates the upper or front portion of the button form and 11 the rear or back of the form. The front 40 of the form may be circular or of any other outline and has a flat or curved top as shown, which may be made of sheet metal 12 stamped to the desired form and provided with a filling block 13 attached to the inner side of the sheet metal 12 in any desired manner; or if preferred the part 10 may be made of composition of other material, the whole being integrally formed. In the center of the block 13 or button 45 form 10 is a cylindrical depression 14, the walls of which are threaded for a purpose to be described later. The marginal edge 15 of the form 10 is of cylindrical or other cross sectional shape and extends in rear 50 of the front portion 10 of the button form. At two diametrically opposite points, the

edge 15 is provided with inwardly projecting lugs 16, each of which may be formed by making two parallel cuts in the cylindrical portion 15 and forcing the metal between the cuts inwardly. Over the form 10, textile material of any kind for covering the button is placed and its edges folded inwardly over the edge 15 of the form being retained in place by an annular holding 60 member or ring 17 made of sheet metal of a width substantially equal to the length of the cylindrical edge portion 15 of the form 10 and of such diameter as to snugly fit within the form after the cloth has been 65 placed in position. At suitable points the ring 17 is provided with notches 18 into which the lugs 16 enter and prevent rotation of the ring and, therefore displacement 70 of the cloth cover.

For the purpose of holding the ring 17 in place and to provide means for the attachment of the button to a garment, the rear or back 11 of the form includes a plate 19 of a shape similar to that of the form 80 10, from the center of which on its front side there projects a stud 20 threaded at 21 to engage the depression 14 to hold the parts in place. At this time the peripheral edge of the plate will bear upon the outer edge 85 of the ring 17 and hold it against any outward movement, the lugs 16 engaging the notches 18 and preventing inward movement of the ring. Any suitable means may be mounted on the plate for fastening the 90 button to a garment, the means here shown consisting of an enlargement 22 on the outer face of the plate through which is formed a perforation 23 for the attaching thread to pass through.

If desired, the plate 19 may be made larger than the diameter of the form 10 and its edge folded, as at 24, Fig. 3, to form a bead or other border surrounding the button, which may be colored or otherwise 100 ornamented.

A further modification may be made by dispensing with the separate ring 17 and pressing the plate 19 into cup-shape as in Fig. 4, the marginal edge 25 of the plate 105 19 serving, in place of ring 17, as a means for retaining the folded edge of the cloth in place on the form 10.

The foregoing description and the drawings have reference to what may be considered the preferred, or approved form of my invention. It is to be understood that

I may make such changes in construction and arrangement and combination of parts, materials, dimensions, et cetera, as may prove expedient and fall within the scope of the 5 appended claims.

Having thus fully described my invention, what I claim as new and desire to secure by Letters Patent, is:

1. A separable button form comprising a 10 cupped front member whose rear edge is cylindrical and provided with inwardly projecting lugs, a fabric covering this member and turned inward under its edge, a ring fitting within said edge and provided with 15 notches receiving said lugs, a rear member engaging the rear edge of the front member and ring, and a screw connection between said front and rear members.

2. A separable button form comprising a 20 front member open at its rear and designed to be covered with textile material, an annular member fitting within the front member and forming a clamp to hold the textile material over the front member, lugs 25 projecting inwardly from the sides of the front member engageable with notches in the annular member to prevent rotation of the latter member, a rear member adapted to bear against the annular member and 30 hold the same in place and also against the

edge of the front member, and a threaded stem on the rear member engageable with a threaded depression in the front member.

3. A separable button form comprising a 35 cup-shaped sheet metal front member, a block within said cup-shaped member partly filling the same and rigidly secured to said member, an annular member slideable within the front member and designed to hold a strip of textile material covering the front 40 member in position thereon, the margins of said textile material being held between the annular member and the wall of the front member, lugs projecting inwardly from the front member engageable with notches in 45 the annular member to prevent rotation thereof, a plate-shaped rear member adapted to bear against the edge of the annular member and the folded textile material to assist in holding them in place, and a 50 threaded stem on the rear member engageable with a threaded depression in the filling block of the front member.

In testimony whereof I affix my signature in presence of two witnesses.

BERTHA M. GEEN.
